UNITED STATES PATENT OFFICE

139,452

DESIGN FOR AN AUTOMOBILE

Leo J. O'Kane, Bayonne, N. J.

Application January 7, 1943, Serial No. 109,214

Term of patent 14 years

(Cl. D14—3)

To all whom it may concern:

Be it known that I, Leo J. O'Kane, a citizen of the United States, residing at Bayonne, in the county of Hudson and State of New Jersey, have invented a new, original, and ornamental Design for an Automobile, of which the following is a specification, reference being had to the accompanying drawing, forming part thereof.

I claim:

The ornamental design for an automobile, as shown.

LEO J. O'KANE.
